UNITED STATES PATENT OFFICE.

CHARLIE D. OBERHOLTZER, OF MARSEILLES, ILLINOIS.

DESIGN FOR A LOCK.

48,604.

Specification for Design.

Patented Feb. 22, 1916.

Application filed August 27, 1915. Serial No. 47,670. Term of patent 7 years.

To all whom it may concern:

Be it known that I, CHARLIE D. OBERHOLTZER, a citizen of the United States, residing at Marseilles, in the county of La Salle and State of Illinois, have invented a new, original, and ornamental Design for a Lock, of which the following is a specification, reference being had to the accompanying drawing, forming a part thereof.

The figure is a perspective view of a lock, showing my new design.

I claim:

The ornamental design for a lock as shown.

CHARLIE D. OBERHOLTZER.

Witnesses:

MINNIE ALLEN,
HELENA OBERHOLTZER.
